UNITED STATES PATENT OFFICE.

HARRY G. WELSH, OF ASHLAND, KENTUCKY.

APPARATUS FOR DISLODGING DRILLING-TOOLS.

1,345,299.

Specification of Letters Patent. Patented June 29, 1920.

Application filed February 26, 1919. Serial No. 279,407.

To all whom it may concern:

Be it known that I, HARRY G. WELSH, of Ashland, in the county of Boyd and State of Kentucky, have invented certain new and useful Improvements in Apparatus for Dislodging Drilling-Tools; and I do hereby declare the following to be a full, clear, and exact description of the invention, such as will enable others skilled in the art to which

10 it appertains to make and use the same.

My invention relates to apparatus used for loosening up a string of tools which has become caught in the operation of drilling oil, gas, or other, wells by the process of 15 churn drilling, and the object of the invention is to provide a simple and highly efficient tool which is designed to be attached to the end of a column of pipe, or casing, and dropped over the string which may 20 have become lost or fast so that the tool may be worked around the bit at the end of the string and the latter more quickly released than by the present method of drilling alongside the string with a solid spud 25 secured to the rigging rope.

In the accompanying drawings, Figure 1 is a vertical sectional view of a column of pipe with my improved spud attached thereto, a portion of a string of tools being 30 shown in full lines. Fig. 2 is an enlarged perspective view of the spud detached.

The column of pipe, more commonly called the casing, is shown at 1 in the drawings, and at 2 is shown a portion of a string 35 of tools, including a bit, an auger stem and jars. My improved spud 3 has a cylindrical hollow head 4, the upper extremity being screw threaded, as at 5, to fit a coupling sleeve 6 on the lower end of the casing 1. 40 The spud is cut away throughout the greater portion of its length to form a semi-cylindrical blade portion 7 which is adapted to work about the bit or other lost or fast tool.

In the use of my device, when a string of 45 tools has become wedged or lost in the well,

the spud is attached to the lower end of casing, sufficiently long to cover the length of the tools in the well, and which is in turn attached by the commonly-used substitute or coupler to the tool joint and the rigging. 50 The spud may likewise be coupled direct to the tool joint by a substitute or coupler for drilling around a bit that may have broken off the string of tools. In either case the spud is then lowered into the well over the 55 tools or bit and operated to drill around the same. The spud fitting closely around tools and being connected with the casing is readily and effectively handled in the drilling operation. 60

When the tools have become dislodged the casing may be again withdrawn and the spud removed.

The advantages of my invention are apparent. It will be seen that in the use of 65 my improved device there is a saving in time and in cost of materials over the methods and long solid spuds heretofore used in drilling alongside fast or lost strings of tools. 70

I claim as my invention:

1. Apparatus for use in dislodging tools from wells including a column of pipe and a hollow spud secured to the end of said pipe, said spud having a semi-cylindrical 75 blade-like cutting portion, said casing and said spud being adapted to surround said tool.

2. Apparatus for use in dislodging tools from wells including a column of pipe and a hollow spud secured to the end of said pipe, said spud being cut away throughout a greater portion of its length to form a semi-cylindrical blade-like cutting portion, said 80 casing and said spud being adapted to surround said tool. 85

In testimony whereof I have signed this specification.

HARRY G. WELSH.
